No. 699,112.

Patented Apr. 29, 1902.

W. I. POST.

STOP MOTION FOR RIBBON LOOMS.

(Application filed Nov. 1, 1901.)

(No Model.)

UNITED STATES PATENT OFFICE.

WILLIAM I. POST, OF PATERSON, NEW JERSEY, ASSIGNOR OF ONE-THIRD
TO JACOB COHEN, OF PATERSON, NEW JERSEY.

STOP-MOTION FOR RIBBON-LOOMS.

SPECIFICATION forming part of Letters Patent No. 699,112, dated April 29, 1902.

Application filed November 1, 1901. Serial No. 80,739. (No model.)

To all whom it may concern:

Be it known that I, WILLIAM I. POST, a citizen of the United States, residing in Paterson, in the county of Passaic and State of New Jersey, have invented certain new and useful Improvements in Stop-Motions for Ribbon-Looms; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates to looms; and it has reference particularly to ribbon-looms. In this class of looms damage often occurs to the goods being woven because by an irregularity in the operation of the parts the shuttles 20 stand in the shed interposed between the reeds and the webs when the batten moves forward to beat up the wefts. What is known as a "smash-protector" is usually made use of to prevent damage occurring to the goods; 25 but this expedient is not perfectly satisfactory—in fact, it is a highly-impractical means for overcoming the difficulty, since so long as a shuttle is interposed between the reed and the web and the batten continues under 30 power to beat up as usual to the full extent it is impossible to avoid entirely the possibility of some damage resulting.

The object of this invention, therefore, is to provide means whereby should the shuttles stand between the reeds and the webs at 35 any time while the beating up is in progress the power will be immediately thrown off and the loom at once stopped.

My invention will be found fully illustrated 40 in the accompanying drawings, wherein—

Figure 1 is a front view of enough of the end portion of a loom to properly show my invention in position thereon. Fig. 2 is a sectional view of the loom, taken just to the right 45 of my mechanism as it is seen in Fig. 1. Fig. 3 is a top plan view of what is seen in Fig. 1. Fig. 4 is an enlarged top plan view of the left-hand portion of my invention as seen in Fig. 1; and Fig. 5 is an enlarged top plan view 50 of the right-hand portion of my invention, a part of the breast-beam being broken away to reveal certain details of construction.

In said drawings, *a* and *b* designate, respectively, the breast-beam and the batten, arranged as usual in the frame *c*. 55

d denotes the shuttle-blocks, *e* the shuttles, *f* the rack, *g* the shuttle-driving pinions, and *h* the reeds, and *i* is the cloth-beam, all arranged as usual on the batten.

j and *k* are bearing-brackets in which is 60 journaled on the batten a shaft *l*, said shaft penetrating the end shuttle-block and carrying a pinion *m*, which engages the teeth of the rack *f*. The front end of this shaft also carries another pinion *n*, which engages with 65 a gear *o*, that is journaled on a bracket *p*, secured to the face of the batten. This gear is provided with a crank *q*.

In brackets *r*, secured to the front face of the batten *b*, is adapted to slide a rod *s*. This 70 rod is adapted to be operated from the crank *q* through the medium of a connecting-rod *t*, whose ends are pivoted on studs *u* and *v* on the rod *s* and the crank *q*, and which is formed in two parts adjustably connected by 75 bolts *w*, which penetrate slots *x* in one of the parts, so as to afford adjustment. The rod *s* carries a thimble *y*, into which is screwed a socket *z*, carrying a buffer 1, which is pressed normally outwardly by a spring 2 in said 80 socket, its movement being limited by a pin 3, which it carries and which works in a slot 4 in said socket.

5 designates a block which is arranged for movement slightly inwardly and outwardly 85 with reference to the breast-beam, in which it is held by means of bolts 6. In order to permit of the movement of the block referred to, it will be understood that the nuts on the bolts are not screwed up tight. The outer 90 face of this block is preferably protected by leather or other soft and durable guard 7.

If the parts are working regularly, when the batten is back the buffer 1 will stand opposed to the block 5, and when the batten is 95 in its extreme forward position, the rack having meantime shifted the buffer to the left, (through the pinion *m*, shaft *l*, pinion *n*, gear *o*, crank *q*, connecting-rod *t*, and rod *s*,) the buffer will stand beside the block and at the 100 left thereof, as shown in dotted lines in Fig. 5. Its normal motion is therefore relatively to the other parts an oblique one. In order to insure the buffer's clearing the block, a sec-

tion thereof is removed, as at 8. (See Fig. 5.) If there is an irregularity in the action of the parts, so that the shuttles are not entirely withdrawn from between the reeds and the 5 webs when the batten beats up, the buffer 1 will contact with the block 5 and press it toward the breast-beam.

9 designates brackets in which is arranged a slide-rod 10, which is normally pressed to 10 the left by a spring 11, interposed between a pin 12 on said rod and one of the brackets. A pin 13 on the breast-beam engages a recess 14 in the rod and normally holds it against the tension of its spring in the position shown 15 in Fig. 5; but the rod has a slight lateral movement in its brackets, so that if it is displaced laterally, so as to disengage the pin 13 from its recess, the spring will immediately throw the rod to the left. This displacement 20 is adapted to be effected by pins 15, loosely arranged in the breast-beam and interposed between the block 5 and the rod 10.

16 denotes the usual hand-rail for working 25 through the lever 17 the belt-shifter 18. On this hand-rail and opposite the end of the rod 10 is mounted a lug 19. Thus when the rod 10 is released it engages the lug and throws the rod 16 to the left, thus effecting the shifting 30 of the belt 20 from the fast pulley 21 to the loose pulley 22.

In setting the mechanism when the rail 16 is thrown manually to the right in order to 35 shift the belt onto the fast pulley the rod 10 is simply pushed toward the breast-beam, when its recess 14 coincides with the pin 13, thus resulting in setting the block 5 in its operative position.

Having thus fully described my invention, 40 what I claim as new, and desire to secure by Letters Patent, is—

1. In a loom, the combination of a support, 45 a movable spring-pressed part carried by said support and arranged parallel with the batten, means for securing said part to the support in its retracted position, said part being also movable laterally with reference to its direction of movement under pressure by the spring to disengage the securing means, and means for moving said part laterally, substantially as described.

2. In a loom, the combination of a movable 55 part of the power-controlling mechanism of the loom arranged parallel with the batten, the breast-beam, another part adapted to engage said first-named part to actuate the same, a spring normally pressing said last-named part toward the first-named part, means for securing said last-named part to the breast-beam in its retracted position, said last-named 60 part being also movable laterally to disengage the securing means, and means for moving said last-named part laterally, substantially as described.

3. In a loom, the combination, with the bat- 65 ten, a suitable support and a spring-pressed movable part arranged parallel with the bat-

ten and being a part of the power-controlling mechanism of the loom, of a shuttle-driving member mounted on said batten, means for securing said part to the support in its retracted position, said part being movable laterally with reference to its direction of movement under pressure by the spring to disengage the securing means, coöperative parts, one of said parts being carried by said batten and adapted to engage the other to move the same, operative connecting means between said first-named coöperative part and said member adapted to move said part out of alinement with the other coöperative part, 80 and operative connecting means also between said other coöperative part and said part of the power-controlling mechanism, substantially as described.

4. In a loom, the combination, with a stationary part of the loom, of the power-controlling mechanism of the loom, a slide-rod mounted in said part and adapted to engage said mechanism to actuate the same, a spring normally pressing said slide-rod toward said 90 mechanism, means for securing said slide-rod in its retracted position, said slide-rod being movable laterally to effect its release and permit the spring to move the same, a block movably arranged in said part, pins interposed between said block and said slide-rod, and means for moving said block, substantially as described.

5. In a loom, the combination, with the batten and with the power-controlling mechanism of the loom comprising a movable part, 100 of the shuttle-driving rack arranged on said batten, a reciprocating member also mounted on said batten, and operative connecting means between said rack and said member 105 adapted to transmit the movement of the rack-bar coincidentally to said member, said member being movable into and out of contacting opposition to said part, substantially as described.

6. In a loom, the combination, with the batten and with the power-controlling mechanism of the loom comprising a movable part, 110 of the shuttle-driving rack arranged on said batten, a reciprocating member also mounted on said batten, and operative connecting means between said rack and said member adapted to transmit the movement of the rack-bar coincidentally to said member and comprising gearing engaging said rack-bar and a 115 connecting-rod between said member and the gearing, said member being movable into and out of contacting opposition to said part, substantially as described.

In testimony that I claim the foregoing I 120 have hereunto set my hand this 31st day of October, 1901.

WILLIAM I. POST.
